HEATER

Douglas W. Anderson, Palatine, Ill., assignor to The Siegler Corporation, Centralia, Ill., a corporation of Delaware

Filed Aug. 31, 1961, Ser. No. 66,563

Term of patent 7 years

(Cl. D81—10)

The rear of the heater is substantially plain.

I claim:

The ornamental design for a heater, substantially as shown and described.
